UNITED STATES PATENT OFFICE.

CHARLES H. TRUE, OF PHOENIXVILLE, PENNSYLVANIA, ASSIGNOR TO THE RAILWAY MATERIALS COMPANY, OF CHICAGO, ILLINOIS, A CORPORATION OF ILLINOIS.

BRAKE-SHOE.

1,114,942.

Specification of Letters Patent. Patented Oct. 27, 1914.

Application filed October 3, 1912. Serial No. 723,780.

To all whom it may concern:

Be it known that I, CHARLES H. TRUE, a citizen of the United States, residing at Phoenixville, in the county of Chester and State of Pennsylvania, have invented certain new and useful Improvements in Brake-Shoes, of which the following is a specification.

This invention relates to railway brake shoes of the type commonly known as reinforced shoes and has for one of its objects the provision of a shoe provided with a tough ductile metal attaching lug securely anchored to the shoe body so that it will not become separated therefrom should the body be cracked or fractured and so constructed that the lug will be strengthened and reinforced to prevent breakage or distortion thereof.

With these ends in view the invention, certain preferred embodiments of which are illustrated in the accompanying drawings, consists in certain novel features of construction which will be readily understood by reference to the following description.

Referring to the drawings—Figure 1 is a plan view of a brake shoe embodying my invention, the shoe body being indicated in broken lines; Fig. 2 is a longitudinal sectional view through the shoe shown in Fig. 1; Fig. 3 is a bottom view of the reinforcing plate and attaching lug; Fig. 4 is a transverse sectional view through the center of the shoe; and Fig. 5 is a fragmentary perspective view of another form of the invention.

On the drawings, reference character 6 indicates the body of the brake shoe which is preferably cast from suitable metal in any preferred shape with or without inserts of any preferred character. A reinforcing plate 7 is disposed adjacent to the back of the shoe body, said plate being of any well known or desired contour having, if preferred, beveled edges 8 and notches 9, or other indentations or recesses to permit the entrance of the metal of the shoe body for the purpose of forming a locking engagement between the body and the plate. The plate is also shown as provided with longitudinal and transverse slots 10 and 11, respectively, into which the metal of the shoe body is permitted to flow. The end lugs 12 and the guide lugs 13 are preferably formed by the body metal which flows up around the sides and ends of the plate and through the

openings 10. The attaching lug 13 consists of a metal strip or strap stamped and bent to the desired shape illustrated in the drawings. The plate 7 is provided with transversely extending slots or recesses 14 through which the ends of the lug legs 15 are inserted from the top of the plate, the ends being then bent to lie against the under face of the plate as shown, whereby the lug is anchored in position. The legs are preferably narrower than the end portions of the lug above the plate so that shoulders 16 are provided which rest upon the upper face of the plate and retain the lug at the requisite height. The legs of the lug above the plate are provided with suitable aligned keyway apertures 17 for the reception of the usual attaching key by means of which the shoe is secured to a brake head.

In the manufacture of the shoe the reinforcing plate 7 is stamped out to the desired shape and is provided with the transversely extending slots 14 through which the ends 15 of the lug legs are inserted. The metal lying between the slots in the plane of the plate is also cut transversely along the longitudinal axis of the plate and after, or before, the attaching lug has been secured in position the metal lying between the slots is bent upwardly to form two upwardly extending reinforcing members or lips 18 disposed within the body of the lug. These reinforcing members or portions fit approximately between the legs of the lug and beneath the top and serve to strengthen and reinforce the lug thereby preventing breakage or distortion of the same during handling of the shoe and while it is in service. It will be manifest that these reinforcing portions may be bent up simultaneously with the bending of the ends of the lug legs, if preferred, whereby the lug is anchored and provided with the reinforce at one operation. The reinforcing member with the lug anchored thereto is then placed in the mold and the body is cast thereon in the usual manner.

In the form of my invention shown in Fig. 5 the plate 19, which is substantially similar to the plate 7, instead of being provided with the centrally disposed slots 14, is cut at each side to provide recesses 21 spaced apart the requisite distance to receive the ends of the attaching lug legs. The lug in this instance consists of a metal strip or strap stamped and bent to provide

a top or body portion 22 adapted to extend transversely of the shoe and provided at each end with a pair of downwardly projecting legs 23, the spacing between the 5 pairs of legs being sufficient to provide alined keyway openings 24 for the accommodation of an attaching key by means of which the shoe is secured to the brake head in the usual manner. The material at the 10 inner edges of the legs is cut away as shown to form the shoulders 25 which rest upon the upper face of the plate 19 at the inner sides of the recesses to retain the lug at the requisite height above the plate. The 15 ends 26 of the legs which project beneath the plate are bent to engage with the under face of the plate whereby the lug is securely anchored. For the purpose of reinforcing and strengthening the lug the metal at the 20 sides of the plate between the legs 23 is bent upwardly as shown to provide the reinforcing and strengthening members 27 similar in construction to the members 18 previously described, the recesses provided 25 by turning up the metal being disposed in this instance at the sides of the plate instead of at the center as disclosed in the previously described modification. These members which are disposed on each side of the 30 keyway openings 24 serve to strengthen and reinforce the lug and prevent breakage and distortion of the same.

My invention and two of its preferred embodiments will be readily understood 35 from the foregoing without further description and it will be manifest that the structural features disclosed are capable of considerable variation without departing from the essence of the invention or sacrificing any of the material advantages thereof.

I claim:

1. A brake shoe comprising a reinforcing member provided with a recess, an attaching lug having portions thereof extending through the recess and engaged beneath said member, the metal of said member being bent upwardly at the side of the recess, and a body cast on said member.
2. A brake shoe comprising a reinforcing member provided with a recess, an attaching lug having end portions projecting through said recess and engaged beneath said member, the metal of said member being bent upwardly between the said end portions of the lug adjacent the recess, and a body cast on said member.
3. A brake shoe comprising a reinforcing member, an attaching lug having ends projecting through said member and engaged beneath the same, the portion of the lug above said member being provided with alined keyway openings and the metal of the

member at each side of the keyway openings being bent upwardly beneath the top of the 65 lug, and a body cast on said member.

4. A brake shoe comprising a reinforcing member, an attaching lug anchored thereto, said lug being provided with alined keyway openings, the metal of the reinforcing member being upturned at each side of said member 70 to engage with and strengthen said lug, and a body cast on said member.

5. A brake shoe comprising a reinforcing member, an attaching lug having the ends of its legs anchored beneath said member, the metal of the member being bent up within the body of the lug and between the legs thereof to strengthen and reinforce the 80 lug, and a body cast on said member.

6. A brake shoe comprising a reinforcing member, an attaching lug made of ductile metal anchored to said member, said lug being strengthened and reinforced by the 85 metal of the reinforcing member which is upturned from its original plane to lie between and engage with the legs of the lug, and a body cast on said member.

7. A brake shoe comprising a reinforcing 90 member, an attaching lug of ductile metal having the ends of its legs projecting through the reinforcing member and anchored therebeneath, the metal of the reinforcing member being upturned within the 95 lug to reinforce and strengthen the same, and a body cast on said member.

8. A back for a brake shoe having attached thereto a key lug, said key lug being reinforced by the metal of which the back 100 is formed.

9. A back for a brake shoe having a key lug formed of a separate piece of metal made separate therefrom and secured thereto, the metal of said back being bent 105 to reinforce said key lug.

10. A back for a brake shoe having a key lug made separate therefrom and secured thereto, the central portion of said back being slitted and the metal bent upwardly to 110 reinforce the vertical walls of said key lug.

11. A brake shoe comprising a reinforcing back, and an attaching lug secured thereto and providing a keyway aperture, said back being bent to reinforce the lug 115 above the base of said aperture.

12. A brake shoe comprising a reinforcing back, and an attaching lug secured thereto and providing a keyway aperture, said back being bent to engage the sides of 120 the lug above said aperture.

CHARLES H. TRUE.
